UNITED STATES PATENT OFFICE.

ALBERT R. HILL, OF ELMIRA, NEW YORK.

SASH-LOCK.

1,119,599.

Specification of Letters Patent

Patented Dec. 1, 1914.

Application filed March 19, 1914. Serial No. 825,752.

To all whom it may concern:

Be it known that I, ALBERT R. HILL, a citizen of the United States, and residing at Elmira, in the county of Chemung and State of New York, have invented certain new and useful Improvements in Sash-Locks, of which the following is a specification.

This invention relates to certain new and useful improvements in sash locks.

10 The primary object of the invention is to provide an automatic means employed with the ordinary two-sash window and mounted upon the lower sash thereof for the prevention of the opening of either of the sashes 15 but allowing a free movement in closing the same.

20 A further object is to provide a spring-pressed eccentrically-mounted cam roller removably positioned upon a window sash and automatically engaging the contiguous sash and releasably for allowing the opening of the window.

25 A still further object is to provide a sash lock that is easy and cheap to manufacture, one in which there are but few parts, and all of which are interchangeable while at the same time facilitating an automatic locking of the window against opening.

30 With these general objects in view and others that will appear as the nature of the invention is better understood, the same consists in the novel combination and arrangement of parts hereinafter fully described, illustrated in the accompanying drawings, 35 and pointed out in the appended claim.

35 In the drawings forming a part of this application and in which like designating characters refer to corresponding parts throughout the several views—Figure 1 is 40 a vertical transverse sectional view taken through the contiguous portions of the two sashes of a window and showing in side elevation, my improved sash lock operatively positioned in connection therewith, a portion of the same being broken away. Fig. 2 is a front elevation of a portion of the window sashes and illustrating the invention in end elevation. Fig. 3 is a top plan view of the lower sash, and the sash lock positioned thereon, the upper sash being shown in section, and, Fig. 4 is a detail perspective view of the three main elements 50 constituting the invention.

55 Referring more in detail to the drawings, it is herein designed to illustrate my improved sash lock mounted upon the top rail

of the lower sash 10 and frictionally engaging a side rail of the upper sash 11 of the ordinary construction of a two-sash window.

A U-shaped bracket 12 is designed for 60 ready attachment to the top face of the lower sash by means of a screw 13 projecting through the bottom perforation 14 and entering the top rail of the sash and whereby the bracket is positioned, the channel 65 thereof opening toward and away from one side rail of the upper sash as herein illustrated, while as will be evident, the top of the bracket remains open.

The parallel side walls 14 of the bracket 70 have their corners cut-away adjacent to the upper sash 11 and provided with notches or half bearings 15 with which are removably journaled the axle 16 positioned eccentrically through the cylindrical locking member 75 17 which constitutes an engaging cam. The cam 17 is provided with a radially-extending lever 18 having a downwardly-extending lug 19 on the bottom thereof for positioning the top of a helical spring 20 80 positioned therearound and having its bottom seated upon a similar lug 21 carried by the base of the bracket 12 adjacent to the perforation 14 thereof.

From this construction, it will be evident 85 that with the bracket properly positioned upon the top of the lower sash, the cam 17 is journaled for partial rotation therein by seating the projecting ends of the axle 16 within the notches 15 and with the spring 20 90 in its proper position, the expansion of the latter normally engages the cam surface of the cylinder 17 against the side rail of the upper sash 11. With such an engagement between the two sashes, it will be readily 95 apparent that any attempt to open the window by either lowering the upper sash or elevating the lower sash will result in more firmly wedging the cam 17 in contact with the upper sash, thus firmly locking the window closed. A perforation 22 being provided in the free end of the lever 18, a pull cord 23 is serviceably secured therein and adapted upon being pulled to move the lever 18 downwardly and thus rearwardly revolve 100 the cam 17 in the direction denoted by the arrow in Fig. 1, whereby the lock is manually released and the sashes are free to move to an open position.

It is to be noted that the gist of the invention resides in the provision of the horizontal faces or seats 24 rearwardly of the

notches 15 and which notches are formed by a curved continuation of said faces. The locking engagement of the cylindrical face of the cam with the upper sash is at a point 5 substantially in the same horizontal plane as the trunnions 16 and whereby any opening movement of the sashes more firmly contacts the face of the cam and results in an increased wedging of the cam trunnions 10 along the seats 24 and forwardly thereof and seated firmly in the notches 15. On the other hand, a releasing of the cam reduces the pressure of the journaled trunnions upon the notches 15 and allows a sliding movement of said trunnions toward the upper sash slidingly upon the faces 24, it being evident that in dis-assembling the cam cylinder from the bracket, that the trunnions are slid along the faces 24 completely out of 15 said notches. Every locking and releasing movement of the cam results in some slight movement of the trunnions upon the faces 24 and varies the contact pressure of the trunnions upon the notches 15 while the increase of pressure incident to the locking 20 operation necessitates a more firm seating of the trunnions in their journaled positions. 25

It will be noted by reference to Fig. 1 that only one-half of the radii of the trunnions engage with the circumferential walls of the bearings, so that to remove the locking member 17 from the base will only require a slight movement for the purpose. This is of peculiar advantage inasmuch as 30 it will require no removal or disconnection 35

of any of the parts of the structure to permit detachment of the locking member.

The structure is preferably formed by cutting the cylinder 17 from a brass bar and then securing by solder or otherwise 40 the lever 18 within a side slot thereof and driving the axle 16 through an eccentric bore through the cylinder, and while many minor changes may be made in the form, proportion and details of construction, the 45 present embodiments thereof are deemed to be the preferable form of construction.

What I claim as new is:—

A sash lock comprising a bracket having a base provided with a boss and side walls 50 each formed at one end with a bearing having a semi-circular wall terminating in faces extending in planes perpendicular to each other, the lower face of each wall being longer than the upper face and disposed 55 parallel with the base, a non-resilient cylindrical locking member carrying rigid eccentrically-disposed trunnions arranged to engage the bearings only by one-half of their radii, an outstanding lever carried by the 60 locking member and provided with a boss, a spring having its end coils encircling the two bosses, and a flexible releasing member connected with the lever.

In testimony whereof I affix my signature 65 in presence of two witnesses.

ALBERT R. HILL.
